UNITED STATES PATENT OFFICE.

WILLIAM T. ANDERSON, OF CLEVELAND, OHIO.

SAFE FOR TIRED WHEEL RIMS.

1,406,805.

Specification of Letters Patent. Patented Feb. 14, 1922.

Application filed April 16, 1921. Serial No. 461,873.

To all whom it may concern:

Be it known that I, WILLIAM T. ANDERSON, a citizen of the United States, residing at Cleveland, in the county of Cuyahoga and State of Ohio, have invented a new and useful Safe for Tired Wheel Rims, of which the following is a specification.

This invention relates to improvements in safes for spare tired wheel-rims for motor-10 vehicles, and pertains more especially to a safe of the character indicated designed to receive two wheel-rims carrying pneumatic tires.

One object of this invention is to enable 15 housing of said rims in the safe in such a manner that access to one rim does not render the other rim accessible.

Another object is to provide improved 20 means for facilitating the placing of a tired wheel-rim into and its removal from the safe, and to prevent rattling of said rim in the safe.

Another object is to provide improved 25 means for preventing circumferential displacement of a tired wheel-rim in the safe.

Another object is to facilitate the assemblage of the component parts of my improved safe, and to render the safe simple, strong and durable in construction.

30 With these objects in view, and to attain any other object hereinafter appearing, this invention consists in certain features of construction, and combinations and relative arrangements of parts, hereinafter described 35 in this specification, pointed out in the claims, and illustrated in the accompanying drawings.

In said drawings, Figure 1 is a front elevation of my improved safe. Fig. 2 is a 40 left-hand side view. Fig. 3 is a right-hand side view. Fig. 4 is a vertical section taken along the line 4—4 in Fig. 2, looking rearwardly. Fig. 5 is a vertical section taken along the line 5—5, Fig. 1, looking in the 45 direction indicated by the arrows. Fig. 6 is a horizontal section taken along the line 6—6 in Fig. 5, looking inwardly, and portions are broken away in Fig. 6 to more clearly show the construction. Fig. 7 is a 50 forward end view of one of the devices employed in preventing displacement, endwise of the safe, of a tired wheel-rim in the safe. Fig. 8 is a horizontal section taken along the line 8—8 in Fig. 1, looking downwardly. 55 Fig. 9 is a front view of a device employed in preventing circumferential displacement

of a tired wheel-rim in the safe. Fig. 10 is a section taken along the line 10—10 in Fig. 9, looking in the direction indicated by the arrows. Figs. 5, 6, 7, 8, 9 and 10 are 60 drawn on a larger scale than Figs. 1, 2, 3 and 4.

The safe illustrated in said drawings is annular, as shown in Figs. 1 and 4, and (see Figs. 2, 3, 5 and 8) comprises an annular 65 rearward metal section 12 which forms the rear end of the safe. An annular chamber 13 for receiving a tire-carrying rim is formed interiorly of said section 12 and extends to the forward extremity of said 70 section. Said chamber 13 (see Figs. 5, 6 and 8) has a rear end wall 14, and a wheel-rim 15, carrying an inflated pneumatic tire 16, is shown in the chamber 13. The section 12 is adapted to be rigidly secured in place on 75 a motor-vehicle in any approved manner, and 17 and 18 indicate the outer surrounding wall and the opposite inner annular wall respectively of the chamber 13. Preferably the walls 14, 17 and 18 are formed of a 80 single sheet-metal stamping.

My improved safe (see Figs. 2, 3 and 5) also comprises an intermediate annular metal section 20 forming a door for controlling access to the chamber 13 in the rearward section 12. An annular chamber 21 for receiving a tire-carrying rim is formed 85 interiorly of the section 20 and extends to the forward extremity of said section. A wheel-rim 22, carrying an inflated pneumatic tire 23, is shown in the chamber 21. The intermediate section 20 is connected to the rear section 12 as will hereinafter appear, and has formed in its rear end an annular chamber 25 which, in the closed 90 position of said intermediate section, registers with the chamber 13 in said rearward section and insures adequate room for the inflated tire 16 on the rim 15 in said chamber 13. Preferably the outer surrounding 95 walls of the chambers 21 and 25 are formed by a circular sheet-metal outer shell 26, and Fig. 5 shows the rear end of said shell as embracing the forward end of the rear section 12, and preferably the opposite or inner annular walls of said chambers are formed by an annular sheet-metal inner shell 27 which is concentric in relation to the outer shell 26 and overlaps the outer side of the inner annular side wall 18 of the chamber 13 of the rearward section 12. The intermediate section 20 comprises an annular 100

sheet-metal plate 29 which faces endwise of said section and is arranged to form a partition between the chambers 21 and 25, and said plate is provided, at its outer circumference, with a rearwardly projecting annular flange 30 riveted, as at 31, to and embraced by the outer shell 26 of said section, as shown in Fig. 5. The plate 29 also has a rearwardly projecting annular flange 32 embracing the inner shell 27 and riveted, as at 33, to said shell. The outer shell 26 of the intermediate section 20 (see Figs. 3 and 4) is shown hinged at its rear end, as at 34, at the right-hand side of the safe, to the forward end of the rearward section 12, and preferably the hinge-connection between said sections 12 and 20 has its axis substantially vertical, and locking means, as at 35, at the opposite side of the safe, are provided for locking said outer shell of said intermediate section to said rearward section in the closed position of said intermediate section. Means for hinging a movable section of a safe to a relatively stationary section, and means for locking said movable section closed against said relatively stationary section are too well known in the art to require further illustration and description in this specification. Adjacent ends of the intermediate and rear sections of the safe are so contoured that the intermediate section, when it is unlocked from the rear section, is free to be swung in a horizontal plane the extent required to afford adequate access to the chamber 13 in said rear section to permit the removal of a tired wheel-rim from, or its entrance into, said chamber.

My improved safe (see Figs. 1, 2, 3 and 5) also comprises a forward annular sheet-metal section 36 forming a door for controlling access to the chamber 21 in the intermediate section. Said forward section 36 has an interior annular chamber 37 which, in the closed position of said section, registers with the chamber 21 in the intermediate section and insures adequate room for the inflated tire 23 on the rim 22 in the last-mentioned chamber. The forward section 36 (see Fig. 3) is shown hinged, as at 38, at its outer circumference and at the right-hand side of the safe, to the forward end of the outer shell 26 of the intermediate section 20, and locking means, as at 39 in Figs. 1 and 2, at the opposite side of the safe, are provided for locking said forward section, in its closed position, to the intermediate section, and preferably the hinge-connection between said forward section and the intermediate section has its axis substantially vertical. Obviously the forward section 36, when it is unlocked from the intermediate section 20, is free to be swung in a horizontal plane the extent required to afford adequate access to the

chamber 21 in said intermediate section to permit the removal of a tired wheel-rim from, or its entrance into, said chamber.

In each of the chambers 13 and 25 (see Figs. 1, 4, 5 and 6) are metal plates 40 spaced circumferentially of the inner annular wall of the respective chamber, as shown in broken lines in Figs. 1 and 4. Each plate 40 (see Figs. 5 and 6) is arranged at and transversely of the inner annular wall of the chamber containing said plate and riveted, as at 41, to said wall, and has an outwardly offset portion 42 which is arranged to extend transversely of the inner circumferential surface of a wheel-rim 70 placed in the desired position in said chamber. The outwardly facing outer part of the offset portion 42 of each plate 40 has two slits 43 extending rearwardly from the forward extremity of said portion of the plate and has the portion between said slits participating in the formation of a resilient member 45 extending forwardly of the plate. The resilient member 45 of each plate 40 is only connected at its rear end 75 to the remainder of and integral with the plate. The offset portion 42 of each plate 40 is provided, rearward of the resilient member 45 of the plate, with an outwardly projecting member 46 arranged to form an abutment for the rear side of a wheel-rim placed in the chamber containing said plate. The relative arrangement of the parts is such that a wheel-rim, upon being placed in the required position in the chamber 13, or in the chamber 21, as the case may be, surrounds the inner annular wall of the respective chamber, and that the rear side of the rim abuts against the forward side of the abutment-member 46 of each plate 40 80 interposed between said rim and said wall. The resilient member 45 of each plate 40 extends forwardly of the space shown occupied by the wheel-rim extending across said plate and has its forward portion bent or 85 contoured to form a sloping shoulder 47 next forward of said space, and said shoulder faces rearwardly and in the direction of the outer circumference of the safe and is arranged to prevent forward displacement 90 of said rim. The resilient member 45 of each plate 40 is provided, at the outer end of its shoulder 47, with a sloping surface 48 extending forwardly from said end of said shoulder and facing in the direction of the outer circumference of the safe and forwardly, so that a tire-carrying wheel-rim, during manual movement thereof into the desired position in relation to said plate, makes contact with said sloping surface and 95 actuates said resilient member inwardly against the action of its resilience, and the relative arrangement of the parts is such that said resilient member by the action of its resilience is returned into its normal position 100

- sition, shown in Fig. 5, as soon as said rim has been moved into contact with the abutment-member 46 of said plate. It will be observed that, by means comprising the plates 40 in each wheel-rim-receiving chamber and their abutment-members 46 and the shoulders 47 of the resilient members 45 of said plates, rattling of a wheel-rim in said chamber is prevented. The offset portion 42 of each plate 40 is provided, at its forward end, with flanges 49 which project into contact with the inner annular wall of the chamber containing said plate, and said flanges are arranged between opposite sides respectively of said portion of the plate and the adjacent slit 43 and are helpful in reinforcing said offset portion at its forward end. One of the plates 40 is shown detached in Fig. 7.
- 10 The safe formed by the sections 12, 20 and 36 is shown enlarged substantially radially inwardly, as at 50, (see Figs. 1 and 4) at two points arranged at opposite sides respectively of the opening 51 formed centrally and extending from front to rear of the safe and surrounded by said sections of the safe, so as to substantially correspondingly enlarge the chambers 13 and 21 at each of said points, as at 52, and make adequate room for the hands to be employed in introducing a tired wheel-rim into or in removing it from the safe. One of the inward enlargements 52 of each of the chambers 13 and 21 is for receiving the valve-stem 53 of the tire of a wheel-rim placed in the respective chamber. The plate 29 of the intermediate section 20 (see Fig. 8) is provided with a member 55 arranged to form a reinforcing partition in the valve-stem-receiving enlargement 52 of the chamber 21 in said section.
- In the valve-stem-receiving enlargement 52 of each of the chambers 13 and 21 of the safe (see Fig. 8) is a rearwardly yieldable resilient member 56 which has one end thereof free and arranged adjacent the main and rim-receiving portion of the respective chamber and extends substantially radially of and through said enlargement of said chamber and is riveted at its other end as at 57, to the adjacent wall of said enlargement of said chamber. Preferably said resilient member 56 is rearward of the valve-stem-receiving portion of said enlargement 55 of said chamber and terminates at its free end in a forwardly projecting arm 58 which (see Figs. 8, 9 and 10) has a longitudinal slot 59 extending to the forward extremity of the arm and arranged to be engaged by the valve-stem 53 of the tire of a rim placed in said chamber, and the longitudinal walls of said slot are adapted to cooperate with said stem in preventing circumferential displacement of said rim. The yielding characteristic and illustrated arrangement of said
- resilient member 56 prevent undue strain on or injury to the valve-stem should said stem strike against the forward end of the slotted arm 58 before entering the slot 59 in the arm. A resilient member 56 is shown detached in Figs. 9 and 10, and a valve-stem 53 is shown in broken lines in Fig. 10 to illustrate the position of said stem in relation to the slotted arm 58 of said resilient member.
- 15 What I claim is—
1. In a safe of the character indicated, a rearward section having an interior chamber which is adapted to receive a tired wheel-rim and extends to the forward extremity of said section and has a rear end wall, an intermediate section hinged to said rearward section and forming a door for controlling access to said chamber and having formed therein a chamber which is adapted to receive a tired wheel-rim and extends to the forward extremity of said intermediate section, means for locking said intermediate section in its closed position to the rearward section, a forward section hinged to said intermediate section and forming a door for controlling access to the last-mentioned chamber, and means for locking the forward section in its closed position to the intermediate section.
  2. In a safe of the character indicated, a rearward section having a wheel-rim-receiving interior chamber extending to the forward extremity of said section, an intermediate section forming a door for controlling access to said chamber and having formed therein a wheel-rim-receiving annular chamber extending to the forward extremity of said intermediate section, and a forward section forming a door for controlling access to the last-mentioned chamber, the outer surrounding wall of said last-mentioned chamber being formed by a circular shell hinged at its rear end to the rearward section, and the opposite and inner annular wall of said last-mentioned chamber being formed by an annular metal shell which is concentric in relation and connected to said outer shell.
  3. In a safe of the character indicated, a rearward section having an interior chamber extending to the forward extremity of said section, an intermediate section hinged to said rearward section and forming a door for controlling access to said chamber and having formed therein an annular chamber which extends to the forward extremity of said intermediate section and also having an annular chamber which is formed in the rear end of said intermediate section and, in the closed position of said intermediate section, registers and communicates with the aforesaid chamber in the rearward section, and a forward section hinged to said intermediate section and forming a door for

controlling access to the first-mentioned chamber in the intermediate section.

4. In a safe of the character indicated, a rearward section having an interior annular chamber which extends to the forward extremity of said section, an intermediate section forming a door for controlling access to said chamber and having formed therein an annular chamber which extends to the forward extremity of said intermediate section and also having an annular chamber which is formed in the rear end of said intermediate section, and, in the closed position of said intermediate section, registers and communicates with the aforesaid chamber in the rearward section, and a forward section forming a door for controlling access to the first-mentioned chamber in the intermediate section, the outer surrounding walls of the chambers in the intermediate section being formed by a metal shell hinged to the rearward section, the inner walls of said chambers in said intermediate section being formed by a metal shell, and the intermediate section also comprising means for tying together and bracing apart said shells.

5. In a safe of the character indicated, a rearward section having an interior annular chamber extending to the forward extremity of said section, an intermediate section hinged to said rearward section and forming a door for controlling access to said chamber and having formed therein an annular chamber which extends to the forward extremity of said intermediate section and also having an annular chamber which is formed in the rear end of said intermediate section and, in the closed position of said intermediate section, registers and communicates with the aforesaid chamber in the rearward section, and a forward section forming a door for controlling access to the first-mentioned chamber in the intermediate section, the intermediate section comprising an annular member arranged between the aforesaid chambers in said section and rigid with the inner and outer walls of said chambers.

6. In a safe of the character indicated, a rearward section having an interior chamber which extends to the forward extremity of said section, an intermediate section forming a door for controlling access to said chamber and having formed therein an annular chamber which extends to the forward extremity of said intermediate section and also having an annular chamber which is formed in the rear end of said intermediate section and, in the closed position of said intermediate section, registers and communicates with the aforesaid chamber in the rearward section, and a forward section forming a door for controlling access to the first-mentioned chamber in the intermediate section, the outer walls of the

chambers in the intermediate section being formed by a metal shell hinged to the rearward section, the inner walls of said chambers in said intermediate section being formed by a metal shell, and said intermediate section comprising a member which is arranged between said chambers in said section and has a flange embracing and secured to the last-mentioned shell and also has a flange embraced by and secured to the aforesaid outer shell.

7. In a safe of the character indicated, a rearward section having an interior annular chamber which extends to the forward extremity of said section and is adapted to receive a wheel-rim having a pneumatic tire and enlarged substantially radially inwardly to receive the valve-stem of said tire, an intermediate section hinged to said rearward section and forming a door for controlling access to said chamber and having formed therein an annular chamber which extends to the forward extremity of said intermediate section, and is adapted to receive a wheel-rim having a pneumatic tire and enlarged substantially radially inwardly to receive the valve-stem of the last-mentioned tire, and a forward section forming a door for controlling access to the last-mentioned chamber.

8. In a safe of the character indicated, a rearward section having an interior chamber which extends to the forward extremity of said section and is adapted to receive a wheel-rim having a pneumatic tire and enlarged substantially radially inwardly to receive the valve-stem of said tire, an intermediate section hinged to said rearward section and having formed therein an annular chamber which is adapted to receive a wheel-rim having a pneumatic tire and extends to the forward extremity of said intermediate section and enlarged substantially radially inwardly to receive the valve-stem of the last-mentioned tire, and a forward section for controlling access to the last-mentioned chamber, the intermediate section comprising an annular plate which is arranged at the rear end of said last-mentioned chamber and ties together and braces apart the outer and inner walls of said chamber, and said plate being provided with a member arranged to form a reinforcing partition in the valve-stem-receiving enlargement of said last-mentioned chamber.

9. In a safe of the character indicated, a section having an interior annular chamber which extends to the forward extremity of said section and is adapted to receive a fired wheel-rim, and plates arranged at and transversely and spaced circumferentially of and secured to the inner wall of said chamber, each plate having an outwardly offset portion which is arranged to extend transversely of the inner circumferential surface of a

- wheel-rim placed in the desired position in said chamber and has two spaced slits extending rearwardly from its forward extremity and has the part thereof between said 5 slits forming a portion of a resilient member extending forwardly of the plate, said resilient member having its forward end portion arranged and contoured as required to prevent forward displacement of said rim in 10 said position of the rim and being integral with the plate.
10. In a safe of the character indicated, a section having an interior annular chamber which extends to the forward extremity of 15 said section and is adapted to receive a tired wheel-rim, and plates arranged at and transversely and spaced circumferentially of and secured to the inner wall of said chamber, each plate having an outwardly offset portion which is arranged to extend transversely 20 of the inner circumferential surface of a wheel-rim placed in the desired position in said chamber and has two spaced slits extending rearwardly from its forward extremity and has the part between said slits 25 forming a portion of a resilient member extending forwardly of the plate, said resilient member being integral with said offset portion of the plate and having its forward end portion arranged and contoured as required to prevent forward displacement of said rim 30
- in said position of the rim, and said offset portion of the plate being provided at its forward end with flanges which project into contact with the aforesaid wall and are arranged between opposite sides respectively of 35 said portion and the adjacent slit.
11. In a safe of the character indicated, an annular section having an interior annular chamber which extends to the forward extremity of said section and is adapted to receive a wheel-rim having a pneumatic tire, said chamber being enlarged substantially radially inwardly to receive the valve-stem of said tire, and a rearwardly yieldable resilient member which has one end thereof free and arranged adjacent the main and rim-receiving portion of said chamber and extends substantially radially of and through the inward enlargement of the chamber and 40 is secured at its other end to the adjacent wall of said enlargement of the chamber, said resilient member being rearward of the valve-stem-receiving portion of said enlargement of the chamber and terminating at its 45 free end in a forwardly projecting arm having a longitudinal slot which extends to the forward extremity of the arm and is adapted to be engaged by the aforesaid valve-stem.
- In testimony whereof I sign the foregoing 50 specification this 11th day of April, 1921.

WILLIAM T. ANDERSON.
